METHOD OF VACUUMIZING CONTAINERS

Filed Aug. 19, 1931

UNITED STATES PATENT OFFICE

ALFRED L. KRONQUEST, OF SYRACUSE, NEW YORK, ASSIGNOR TO CONTINENTAL CAN COMPANY, INC., OF NEW YORK, N. Y., A CORPORATION OF NEW YORK

METHOD OF VACUUMIZING CONTAINERS

Application filed August 19, 1931. Serial No. 553,108.

The invention relates to new and useful improvements in a method of vacuumizing a container containing a powdered food product. One of the common methods of vacuumizing a container having a powdered food product therein consists in loosely attaching the cover to the container, then placing the container in a vacuum chamber and drawing the air from the container through the loose connection between the cover and the container body. It is found that the great velocity of the air rushing out of the container through the small orifices or spaces left between the loosely folded metal parts carries with it the powder from the container into the vacuum chamber and leaving in the infolded parts sufficient powdered material to interfere with the proper operation of the seaming rolls in the forming and finishing of the double seam for the joining of the cover to the container body.

An object of the present invention is to provide a method of vacuumizing a container with the cover clinched thereto so as to avoid drawing any of the powdered material from the container after the cover has been secured thereto by clinching or crimping of the metal parts so that they are loosely connected.

In the drawing—

Figure 1 is a view partly in plan and partly in section showing more or less diagrammatically one form of apparatus for carrying out the invention;

Fig. 2 is a view of a container with the powdered material therein and with the cover removed as the container is subjected to the action of a vacuum chamber for withdrawing the air from the powdered material;

Fig. 3 is a view showing the container after the air has been withdrawn from the powdered material and with the cover loosely clinched to the body of the container, and

Fig. 4 is a view similar to Fig. 3, but showing the cover as finally seamed to the container body and the container sealed.

In carrying out the invention, the powdered material is placed in the container in the usual manner, and the container, without any cover being applied thereto, is passed into a vacuum chamber or otherwise con-

nected with a vacuum creating apparatus so that the air in the container and in the powdered material is withdrawn therefrom. When the container is subjected to a twenty-nine inch vacuum with the cover removed, 55 the whole mass of the powder appears to fluff up and then settle back into the container in a more compact space. The loosely packed powdered material when placed in the container contains entrapped air. When the 60 container passes into the vacuum chamber, this entrapped air expands and is drawn from the powdered material, causing first, the fluffing up of the material, and in case of very finely powdered material, a mist of 65 powder in the space surrounding the container. When the container is removed from the vacuum chamber and again subjected to atmospheric pressure, the powder has settled back into the container in a compact condition. The cover is then applied to the container and clinched thereto loosely, after 70 which the container is placed a second time in a vacuum chamber and subjected to a vacuum creating apparatus, and the air 75 drawn from the container will now be free from any powder, and the infolded parts of the metal through which the air passes will also be free from entrapped powder. If the product in the container is to be sealed in 80 vacuum, then the cover is double seamed to the container body while the container is under vacuum. The vacuum in the container may, if desired, be replaced by an inert gas, and the cover then secured to the container 85 body by double seaming.

It is thought that possibly the invention will be better understood by a brief reference to the apparatus shown in the drawing. The containers which are indicated at C are fed on to a disk 1 and conveyed by the disk against a guide rail 2 with which is associated a transfer device 3, and thus the container is placed in one of the pockets 4 of a rotating valve 5. The container is filled to the desired extent with the powdered material. No cover is placed on the container. Associated with the valve 5 is a casing 6 having a chamber 7 which is placed continually under vacuum by a vacuum creating apparatus con- 100

nected in a suitable way with a pipe 8 leading to the chamber 7. As the valve rotates, the pockets will be brought into communication with the chamber 7, and thus it is that each container is subject to the influence of the 5 vacuum chamber and the air withdrawn from the container. The powdered product, as noted above, contains entrapped air when the powder is loosely packed in the container. This subjecting of the container with the 10 cover removed to the influence of the vacuum chamber expands and withdraws the air from the powdered material and from the container. Any powder passing off with the air withdrawn from the container may be collected in a sanitary receptacle associated with the vacuum creating apparatus, and thus waste of material is avoided. Furthermore, in this vacuum chamber 7 there are no operating parts which are likely to be clogged by the powdered material accumulating thereon. The container after it is subjected to the 15 vacuum pull in the chamber 7, and after the air has been withdrawn from the powdered material in the container, is passed to the atmosphere and removed from the valve pocket by a rotating transfer device 9. The rotating transfer device places the container on the conveyor 10 which takes the container into the clinching mechanism indicated diagrammatically at 11. In this clinching mechanism, the cover is applied to the container body, and the flange of the cover and the flange on the container body loosely joined 20 by clinching together. This will hold the cover on the container body, but at the same time, it will permit the air to be withdrawn from the container body. When the container comes out of the first vacuum chamber, 25 the powdered material settles back into the container in a compact form and substantially free from any entrapped air. After the container passes through the clinching mechanism, it is placed by a transfer device 12 in a pocket 13 of a rotary valve 14 which carries the container into the chamber 15. The transfer device 16 removes the container from the pocket of the valve and places the same on a conveyor 17. As the container passes through 30 the vacuum chamber 15, the air is withdrawn from the container, and during this withdrawing of the air, the powdered material does not pass out with the air. Practically the only air in the container after it is covered is the air in the space between the powdered material and the cover, and the withdrawing of this air does not carry with it the powdered material. The container then is taken from the conveyor by a transfer device 18 and placed in a pocket 19 by a valve 20 which carries the container into a chamber 21 in which is located a double seaming mechanism. This double seaming mechanism may include a first and second 35 operation station. The first operation station

is indicated at 22 and the second at 23. The rotating transfer device 24 carries the container first to one station and then the other, and thus it is that the cover is double seamed to the container body and the container sealed. The containers are again placed in the pocket 19 of the valve 20, and a transfer device 25 removes the closed container from the pocket of the valve and places the same on the conveyor 26. 70 75

The container C, as shown in the drawing, comprises a cylindrical body portion, in which a bottom end c' has been secured. The material is indicated at M in the drawing. In Fig. 2, the container is shown with the body thereof flanged, ready for the cover, but no cover has been place thereon. This is the condition of the container as it passes from the vacuum chamber 7. In Fig. 3, a cover c² is shown applied to the container body, and the metal parts of the cover and the body are loosely folded together as indicated at c³. In Fig. 4 of the drawing, the cover c² is shown as secured to the container body by a double seam c⁴ which seals the container. 80 85 90

When it is desired to seal the container with the product thereof in vacuum, then the chamber 21 is placed under vacuum, and the container passes from the chamber 15 into this chamber 21 with the vacuum maintained within the container and the end is double seamed to the container body, thus sealing the container. If it is desired to close the container with the material in an inert gas, then the chamber 21 is charged with an inert gas, such for example, as carbon dioxide. When the container passes into this chamber, the inert gas will pass in through the loosely connected parts of the cover and the container body, thus charging the container with an inert gas. The cover is then double seamed to the body, and this will seal the container with the inert gas therein. 95 100 105

It will be obvious that the apparatus shown may be greatly modified, and is merely illustrative of a type of apparatus that can be used in the carrying out of the improved method of vacuumizing a container. While my improved method is particularly adapted for the vacuumizing and sealing of a container having a powdered material therein, it will also be useful in the vacuumizing and sealing of containers with other kinds of material. 110 115

Having thus described the invention, what I claim as new and desire to secure by Letters-Patent, is—

1. The process of packaging powdered material in sealed containers under vacuum comprising placing the powdered material in a container and subjecting the container to a vacuum before the sealing cover is applied thereto, releasing the vacuum on the container, placing a cover on the container, subjecting the container to a vacuum for with- 120 125 130

drawing the air therefrom, and seaming the cover to the container while maintained under said vacuum.

2. A method of packaging powdered material in sealed containers comprising placing the powdered material in the container and subjecting the container to a vacuum before the sealing cover is applied thereto, releasing a vacuum on the container, placing the cover thereon and loosely securing the cover to the container body, subjecting the container with the loosely attached cover to a vacuum for withdrawing the air therefrom, charging the container with an inert gas, and seaming the cover to the container body while charged with the inert gas.

In testimony whereof, I affix my signature.
